UNITED STATES PATENT OFFICE.

MORRIS UNGER, JOSEPH W. ZARRO, AND BERNARD S. VEAZIE, OF PITTSBURGH,
PENNSYLVANIA.

COLLAPSIBLE SEAT.

1,367,573.

Specification of Letters Patent.

Patented Feb. 8, 1921.

Application filed April 12, 1920. Serial No. 373,152.

To all whom it may concern:

Be it known that MORRIS UNGER, JOSEPH W. ZARRO, and BERNARD S. VEAZIE, citizens of the United States, residing at Pittsburgh, 5 in the county of Allegheny and State of Pennsylvania, have invented certain new and useful Improvements in Collapsible Seats, of which the following is a specification.

10 This invention relates to amusement devices, and more particularly to an ejector and collapsible seat.

One of the main objects of the invention is to provide a seat of the character of simple construction and operation which may be installed at small cost. A further object is to provide a seat having associated therewith a slide or chute, and simple and efficient means for extending the chute and 20 simultaneously depositing a person from the seat on to the chute. Further objects will appear from the detailed description.

In the drawings:—

Figure 1 is a perspective side view, partly 25 in section, of the seat member.

Fig. 2 is a perspective side view of the seat as applied.

Fig. 3 is a front view of the doors and associated parts.

30 Fig. 4 is a side view of the seat, as applied, with the slide extended.

The seat includes a suitable frame 1 which supports a downwardly and forwardly inclined back 2 the lower end of which extends closely adjacent to the seat member 3. This seat member is formed of a plurality of bars 4 secured to the upper runs of chains 5 which pass about aligned sprocket wheels 6 secured on shafts 7 rotatably mounted in 35 frame 1, these shafts being disposed in a common plane and there being two sprockets secured on each shaft as will be readily understood. A covering 8 of carpet or other suitable material is secured over the outer 40 faces of bars 4 to prevent a person upon the seat from being projected during operation of the device.

A slide 9 is provided at the front of the seat. This slide comprises an upper section 50 10 and a lower section 11 which are hingedly connected at their adjacent ends by a rod 12. Section 10 is pivoted at its upper end upon the forward shaft 6, and each side bar 13 of section 11 is provided in its forward 55 portion with a longitudinally extending slot

14. These slots receive a bar 15 secured through the forward ends of two beams 16 which support frame 1. A link 17 is provided at each side of the slide and is pivoted at its rearward end to a rod 17^a which passes 60 through the lower end of a liner 18 pivoted at 19 to frame 1; and at its forward end to rod 12. This lever is attached at 20 to the lower runs of chains 5. Normally the lever is in the position illustrated in Fig. 1. 65 When a person is seated upon member 3, by throwing the lever into the position illustrated in Fig. 4 the chute 9 is extended and raised, and the seat member is moved forwardly so as to deposit the person upon the 70 slide or chute, from which he may be discharged onto an inclined series of rollers or any other suitable device.

A door frame 21 is secured to and supported by beams 16. This frame supports 75 two rods 22, one at each side of the frame, to which are secured hinge leaves 23 which are secured to swinging doors 24 fitting within frame 21. Each rod is provided at its lower end with a rectangularly disposed and inwardly directed crank arm 25 pivotally secured at its forward end to a link 26 the rearward end of which is pivoted on rod 17^a. 80

In practice the lever and associated parts will be concealed, the lever being preferably positioned behind a partition erected adjacent to the seat. As will be understood, an operator stands by the lever, and as soon as one or more persons are seated upon member 3 throws the lever into the 90 position illustrated in Fig. 4, this depositing the persons upon slide 10, the slide being raised and extended and the doors opened simultaneously with operation of the seat. A suitable chute, or other device, may be 95 erected adjacent doors 24 for receiving persons discharged from the slide.

As will be understood, there may be changes made in details of construction and arrangement of parts of the invention without departing from the field and scope of the same, and we intend to include all such variations, as fall within the scope of the appended claims in this application in which a preferred form only of our invention is 105 disclosed.

What we claim is:—

1. In a device of the character described, a substantially and permanently horizontal seat member of the endless belt type, a slide 110

positioned adjacent to the front of said seat member and normally in lowered position, and means for causing forward movement of the seat member and simultaneously raising the slide into position to receive a person discharged from the seat member.

5. 2. In a device of the character described, a substantially and permanently horizontal seat member of the endless belt type, a 10 foldable slide having its upper end positioned adjacent to the front of the seat member, and means for causing forward movement of the seat member and for simultaneously raising and extending said slide.

15. 3. In a device of the character stated, a frame, a seat member supported by the frame for forward and rearward movement therein, a slide pivoted at its upper end to the frame adjacent to the front of the seat member, and means for causing forward 20 movement of the seat member and for raising said slide so as to extend downwardly and forwardly from said member.

4. In a device of the character described, 25 a frame, a seat member mounted in said frame for forward and rearward movement therein, a slide comprising two hingedly connected members, the inner one of said members being pivoted at its upper end to the frame adjacent to the front of said seat member, and means attached to the slide members at the hinge axis thereof and to the seat member for causing forward move- 30

ment of said member and simultaneously raising and extending the slide. 35

5. In a device of the character described, a frame, two shafts rotatably mounted in the frame, sprocket wheels secured on said shafts, chains passed about the sprocket wheels, a seat member carried by the upper 40 runs of the chains, a slide comprising two members hingedly connected at their adjacent ends, the inner one of said members being pivoted at its upper end upon the forward shaft, a lever pivoted intermediate its 45 ends, links connected at their rearward ends to the lower end of the lever and pivoted at their forward ends to the slide members at the hinge axis thereof, and connections between the lever above its pivot and the lower runs 50 of said chains.

6. In a device of the character described, a frame, a seat member mounted in the frame for forward and rearward movement therein, a normally lowered slide, a normally closed door in front of the seat member, and means for causing forward movement of the seat member and simultaneously opening the door raising the slide into position to extend downwardly from the front 60 of said seat member to the doorway.

In testimony whereof we affix our signatures.

MORRIS UNGER.
JOSEPH W. ZARRO.
BERNARD S. VEAZIE.
